WILLIAM S. FERRIS, OF ELKHART, INDIANA, AND ALEXANDER B. LEITH, OF
CHICAGO, ILLINOIS, TRUSTEES.

FOLDING GO-CART.

1,094,418.

Specification of Letters Patent. Patented Apr. 28, 1914.

Application filed February 28, 1908, Serial No. 418,311. Renewed March 9, 1914. Serial No. 823,635.

To all whom it may concern:

Be it known that I, FRANK J. BEIER, a citizen of the United States, residing at Elkhart, in the county of Elkhart and State of Indiana, have invented certain new and useful Improvements in Folding Go-Carts, of which the following is a specification.

This invention relates to improvements in folding go-carts and the primary object of 10 the same is to provide an improved, simple, light and durable device of this character which may be folded into compact form.

A further object is to provide an improved folding go-cart including a lock for holding 15 the parts in an operative position and improved means for yieldingly supporting the seat, which means also serves as a guide and support for the lock during the folding and unfolding operation.

20 To the attainment of these ends and the accomplishment of other new and useful objects, as will appear, the invention consists in the features of novelty and the construction, combination and arrangement of the 25 several parts hereinafter more fully described and claimed and shown in the accompanying drawings illustrating the embodiment of the invention and in which—

Figure 1 is a side elevation of an improved 30 device of this character constructed in accordance with the principles of this invention, showing the same in dotted lines in an adjusted position to permit the occupant to assume a reclining position. Fig. 2 is a top 35 plan view of Fig. 1. Fig. 3 is a detail sectional view on line 3—3 of Fig. 1. Fig. 4 is a detail sectional view on line 4—4 of Fig. 5. Fig. 5 is a detail sectional view of one of the wheel supports. Fig. 6 is a detail view 40 partly in section showing the manner of supporting the seat and of locking the parts in an operative position. Fig. 7 is a detail sectional view on line 7—7 of Fig. 1. Fig. 8 is a detail view in elevation showing the locking 45 bail for one pair of the wheel supports and its connection with one of the arms of the seat.

Referring more particularly to the drawings and in the present exemplification of 50 the invention, the running gear frame preferably comprises spaced side members 10 which are connected at one end by means of a cross bar 11 which stands between the extremities of the side bars and is secured

thereto preferably by means of screws or 55 bolts 12 which pass through suitable clips 13 arranged adjacent the outer face of the side bars 10 and the screws 12 pass into the ends of the cross bar or member 11. Extending transversely across the frame at the rear end 60 thereof is a connecting bar or rod 14 which serves as a means for pivotally securing the side arms 15 of the handle 16 to the running gear frame.

The wheel supports 17 of the running 65 gear frame are preferably constructed of a single piece of suitable material, such as metal or the like, the body portions of which are provided with spaced side flanges 18, which terminate short of the ends thereof. 70 One end 19 of the body portion 17 beyond the side flanges 18 is bent around one of the side bars 10 and the extremity 20 thereof is bent into close proximity to the body portion 17 so as to stand between the flanges 75 18 thereof and is secured against displacement in any desired or suitable manner, preferably by means of a bolt or rivet 21 which passes through the extremity 20 and the body portion 17. The end 19 is so 80 shaped that the wheel support is adapted for rotation with respect to the running gear frame to permit the supports to be folded with respect to the running gear frame. The other extremity 22 of the wheel support 85 beyond the flanges 18 is bent to form a spaced wall 23 which is parallel to the body portion 17 and the extremity 24 thereof is deflected or bent so as to stand adjacent the body portion 17 between the flanges 18 and 90 23 is held from displacement preferably by means of a bolt or rivet 25, which passes through the extremity 24 and the body portion 17.

The wall 23 is provided with an aperture 95 26 through which one end of a stub axle 27 is adapted to pass and this axle is held against displacement with respect to the wheel support in any desired or suitable manner, preferably by means of a reduced 100 threaded extremity 28 passing through the body portion 17 upon which is screwed a suitable nut 29.

The wheel supports are secured to the running gear frame in such position that the 105 wheels 30, which are mounted upon the axles 27 will stand adjacent the outside of the frame, so that when the supports are folded

with respect to the running gear frame, they will assume a position in close proximity thereto. One of the wheel supports is preferably located adjacent each extremity of the side bars 10 and the supports on each side of the frame are connected to move in unison by means of a suitable connecting bar or rod 31, the extremities of which preferably project a short distance beyond the 10 wheel supports. Secured to these bars 31 and adjacent each end thereof is a spaced member 32 (see Fig. 7) and the extremities of this member and the bars 31 are deflected away from each other to form a ready entrance for the locking bail into the space formed between the bar and the members. 15

Pivottally supported adjacent the forward extremity of the running gear frame is a bail 33 which depends below the running gear frame and the side arms thereof are adapted to enter the space between the members 32 and the bars 31 to lock the wheel supports in position. A similar bail 34 is pivottally supported adjacent the rear end of the running gear frame and is adapted to lock the rear extremities of the connecting bars 31 and the rear wheel supports against lateral movement with respect to the running gear frame. 25

30 A suitable cross bar 35 is secured to the running gear frame intermediate the ends thereof for supporting the forward end of the seat 36. Secured to the bottom of the seat 36, preferably adjacent the forward end 35 thereof and by one extremity are spaced loops 37 which are of a length to surround the cross bar 14. These loops, preferably two in number, are bowed slightly upwardly, as shown more clearly in Fig. 6, and are 40 located adjacent the sides of the seat 36. These loops are constructed of any suitable flexible material such as metal or the like, and the seat preferably terminates short of the ends of the loops which surround the 45 cross bar 14, so that the seat will rest upon the loops and be yieldingly supported thereby to form a spring seat.

50 Adjacent each side of the seat 36 are links or bars 38, 39, one extremity of each of which is pivottally connected to the respective side bar 10, and pivottally connected to the free extremities of these bars or links are clips 40 and supported by the clips are arm rests 41. These bars or links 38, 39, extend for 55 any suitable distance above the running gear frame and the rear bars or links 39 are connected to the side arms 15 of the handle 16 by means of suitable links 42 so that the bars or links 38 and 39 will be folded downwardly against the running gear frame when the handle 16 is moved forwardly and downwardly. 60

In order to operate or move the bail 34 to lock or unlock the wheel supports simultaneously with the adjustment of the links 65

38, 39, the bail may be connected to one of the links and for this purpose one arm of the bail may be extended above the running gear frame as at 43, and this extension is preferably deflected rearwardly, as shown, 70 and a link 44 may be pivotally connected by one extremity to the bar 39 and is connected at its free extremity with the extension 43 of the bail 34 by means of a slot 44, which is supported by the extension 43 thereby 75 allowing a lost motion to permit the parts to fold compactly with relation to the running gear frame.

In order to prevent the wheel supports 17 from moving longitudinally on the side 80 bars 10, there may be provided a clip 45 for the two front supports and this clip is secured to the side bars 10 and extends over the portion 19 of the supports which surround the side bars to permit the supports 85 to be moved pivottally with respect to the side bars and the rear wheel supports 17 may be held against longitudinal movement by means of the connecting bars 31 between the respective pairs of wheel supports. 90

A lock 46 is pivotally connected by the extremity of its side arms 47 preferably to the rear bars 39 and is provided with suitable notches 48 (see Fig. 6) in the side arms which are adapted to receive the cross bar 95 14 on the running gear frame to lock the arm rests 41 and the handle 16 in an operative position, as shown in Figs. 1 and 6 of the drawings. When it is desired to fold the arm rests 41 and the links or bars 38, 39 100 with respect to the running gear frame the lock 46 may be raised so as to disengage the cross bar 14 after which the handle 16 may be moved forwardly and downwardly, which will cause the arm rests 41 to move 105 forwardly and downwardly and the lock 46 to move upon and be supported by the loops 37 to prevent the lock from dropping down between the side bars 10 of the running gear frame. Suitable yielding members 49, such 110 as coil springs or the like, may be secured by one extremity to the side arms 47 of the lock 46 and the other extremities to the running gear frame for holding the bail against accidental displacement when the arm rests 115 41 are adjusted to an operative position. The seat 36 is provided with an independently adjustable back 50 which may be supported in position by means of a suitable bail 51 pivotally connected, preferably to 120 the links 42, so that the body portion will engage the rear face of the back and move in a suitable guide 52 secured to the back. A suitable foot rest 53 may also be provided at the forward end of the frame, one extremity of which is preferably secured to the seat 36. The other extremity is preferably supported by means of a bail having side 125 arms 54, one extremity of each of which is preferably connected by means of a bar or 130

member 55 and the other extremities 56 are pivotally connected to any stationary portion of the running gear frame, preferably the cross bar 35, and the arms 54 are of such a length that the cross or connecting bar or member 55 will rest upon the forward cross bar 11 of the running gear frame to hold the foot rest in the position shown in full lines in Figs. 1 and 2 of the drawings to permit the occupant to sit in an upright position on the seat 36 when the back 50 is in the position shown in Fig. 1. When the back 50 is adjusted by means of the bail 51 to the position shown in dotted lines in Fig. 1 of the drawings to permit the occupant to assume a reclining position, the foot rest 53 may be elevated to the position shown in dotted lines in Fig. 1.

Any suitable means may be provided for supporting and locking the foot rest in its elevated position. A suitable and efficient means for accomplishing this purpose comprises a bail having spaced side members 57 (see Fig. 1), the extremities 58 of which are formed into elongated eyes or loops preferably arranged at an angle to the body portion thereof. This bail is preferably pivoted to the connecting bar or member 11 of the running gear frame with the eyes or loops 58 thereof located adjacent the seat 36 when in the position shown in full lines in Figs. 1 and 2 of the drawings, and the side members 54 of the foot rest support respectively pass through the eyes or loops 58. When it is desired to support the foot rest in an elevated position, the spaced members 57 may be raised by their extremities into the position shown in dotted lines in Fig. 1 of the drawings, which will cause the loops or eyes 58 to assume such a position with relation to the connecting bar or member 55 of the foot rest support that the said bars or members thereof will rest in the lowest portion of the loops. When it is desired to lower the foot rest, the members 57 may be moved about their points of pivotal support and toward the seat 36, which will lower the supporting bail 54, 55.

Suitable flexible or pliable members 59, such as fabric or the like, may be secured to the arm rests 41 and the seat 36 to prevent the child from extending its arms beyond the sides of the supporting structure and also to protect its garments.

In order that the invention might be fully understood by those skilled in the art, the details of the foregoing embodiment thereof have been thus specifically described, but

What I claim as new and desire to secure by Letters Patent is—

1. In a folding go-cart, the combination of a seat supporting structure including spaced members, a seat arranged between the said members and out of engagement therewith, means for supporting one end of

the seat, means extending beyond the other end of the seat and engaging the said supporting structure to form a yielding support for the said end, side members for the seat adapted to fold with respect to the supporting structure, and means adapted to engage the supporting structure to lock the side members in operative position, said locking means being adapted to move upon and be supported by the said yielding support when the side members of the seat are being adjusted. 70

2. In a folding go-cart, the combination of a seat supporting structure including spaced members, a seat arranged between the said members and out of engagement therewith, means for supporting one end of the seat, means extending beyond the other end of the seat and engaging the said supporting structure to form a yielding support for the said end, side members for the seat adapted to fold with respect to the supporting structure, and a catch having pivotal connection with the said members of the seat, said catch being provided with a shoulder adapted to engage over a portion of the supporting structure to lock the part in an operative position, the free end of the catch being adapted to move upon and be supported by the said yielding support when the said side members are being adjusted. 80 85 90

3. In a folding go-cart, the combination of a seat supporting structure including spaced members, a seat arranged between the said members and out of engagement therewith, means for supporting one end of the seat, an elastic member, one extremity of which is secured to the seat and the other extremity having engagement with the supporting structure beyond the seat to form a yielding support for the seat, adjustable side members for the seat, and a catch having pivotal connection with the said members and being adapted to engage a portion of the said structure to lock the parts in an operative position, the free end of the catch being adapted to move upon and be supported by the elastic member when the side members are being adjusted. 100 105 110

4. In a folding go-cart, the combination of a seat supporting structure including spaced members, a seat arranged between the said members and out of engagement therewith, means for supporting one end of the seat, an elastic member, one extremity of which is connected to the seat and the other extremity having engagement with the supporting structure beyond the seat to form a yielding support for the seat, one extremity of the said elastic member having a loose connection with its respective element, side members for the seat, and a catch having pivotal connection with the side members and being adapted to engage a portion of the said structure to lock the parts in an op- 115 120 125 130

erative position, the free end of the catch being adapted to move upon and be supported by the elastic member when the side members are being adjusted.

5. In a folding go-cart, the combination of a seat supporting structure including spaced members, a seat arranged between the said members and out of engagement therewith, means for supporting one end of the 10 seat, an elastic member, one extremity of which is secured to the seat and the other extremity having engagement with the supporting structure beyond the seat to form a yielding support for the seat, said elastic 15 member being bowed upwardly and one extremity thereof having a rigid connection and the other extremity a loose connection with their respective elements, side members for the seat, and a catch having pivotal 20 connection with the side members and being adapted to engage a portion of the said structure to lock the parts in an operative position, the free end of the catch being adapted to move upon and be supported by 25 the elastic member when the side members are being adjusted.

6. In a folding go-cart, the combination of a seat supporting structure including spaced members, a seat arranged between 30 said members, means for supporting one edge of the seat, a cross bar between the said members remote from the seat, an elastic member bent upon itself to form a loop and surrounding the cross bar, the free extremities of the member being secured to the seat to form a yielding support therefor, folding 35 side members for the seat, and a catch having pivotal connection with the said side members, said catch being adapted to engage the supporting structure to lock the parts in position, the free end of the catch being adapted to move upon and be supported by the said elastic member when the side members are being adjusted.

45. 7. In a folding go-cart, the combination of a seat supporting structure including spaced members, and a transverse member connecting said spaced members, a seat located beyond the transverse member, means 50 for supporting one edge of the seat, and means for supporting the other edge of the seat comprising a strip of flexible material bent upon itself to form a loop, the body portion of the loop surrounding the said 55 transverse member and the extremities thereof being secured to the seat to form a yielding support for the seat.

8. In a folding go-cart, the combination of a seat supporting structure including 60 spaced members and a transverse member connecting said spaced members, a seat located beyond the transverse member, means for supporting one edge of the seat, means for supporting the other edge of the seat 65 comprising a strip of flexible material bent

upon itself to form an extended loop, the body portion of the loop surrounding the transverse member and the extremities thereof being secured to the seat to form a yielding support for the seat, folding side members for the seat, and a member having pivotal connection with the side members and adapted to engage the supporting structure to lock the parts in position, the free end thereof being adapted to move upon and be 70 supported by the said yielding support between the said transverse member and the seat when the parts are being adjusted. 75

9. In a folding go-cart, the combination of a seat supporting structure including spaced 80 members and a transverse member connecting said spaced members, a seat located beyond the transverse member, means for supporting one edge of the seat, means for supporting the other edge of the seat comprising a plurality of strips of flexible material 85 bent upon themselves to form extended loops, the body portions of the loops surrounding the transverse member and being spaced from each other, and the extremities thereof 90 being secured to the seat adjacent the sides thereof to form a yielding support for the seat, folding side members for the seat, and a member having pivotal connection with the side members and adapted to engage 95 the supporting structure to lock the parts in position, the free end thereof being adapted to move upon and be supported by the said yielding support between the said transverse member and the seat when the parts 100 are being adjusted.

10. In a folding go-cart, the combination of a seat supporting structure, a seat, means for yieldingly supporting the seat upon the said structure, a pair of adjustable uprights 105 pivotally supported by the said structure adjacent each side of the seat and extending above the seat, arm rests, a clip pivotally connected to the extremity of each of the uprights, the extremities of said arm rests 110 being engaged by the respective clips whereby the arm rests will be maintained in a horizontal position with relation to the supporting structure in any of the adjusted positions of the uprights, means movable with the uprights for locking the uprights in position and a guide for said locking means. 115

11. In a folding go-cart, the combination of a seat supporting structure, a seat supported thereby and fixed with respect thereto, a pair of adjustable uprights pivotally mounted by one end on the said structure independent of the seat and adjacent each side thereof and extending above the seat, arm rests, a clip pivotally connected to the 120 extremity of each of the uprights, the extremities of said arm rests being engaged by the respective clips whereby the arm rests will be maintained in a horizontal position 125 with relation to the supporting structure in 130

any of the adjusted positions of the uprights, means connected with one of the uprights and movable therewith for maintaining the uprights in position and a guide for the said means.

12. In a folding go-cart, the combination of a supporting structure, a folding body structure thereon and including side members, a seat arranged between the said members and out of engagement therewith, means for supporting one end of the seat, means extending beyond the other end of the seat and engaging the said supporting structure to form a yielding support for said end, said side members being adapted to fold with the body structure, and means adapted to engage the supporting structure to lock the body structure in operative position, said locking means being movable upon and supported by the said yielding support when the body structure is being adjusted.

13. In a folding go-cart, the combination of a supporting structure including spaced members, a folding body structure embodying a seat arranged between said members, means for supporting one edge of the seat, a cross bar between the said members remote from the seat, an elastic member bent upon itself to form a loop surrounding the cross bar, the free extremities of the member being connected with the seat to form a yielding support therefor, said body structure also embodying folding side members for the seat, and a catch having pivotal con-

nexion with the body structure, said catch being adapted to engage the supporting structure to lock the parts in position, the free end of the catch being adapted to move upon and be supported by the said elastic member when the body structure is adjusted. 35 40

14. In a folding go-cart, the combination of a supporting structure including spaced members, a folding body structure embodying a seat arranged between said members, means for supporting one edge of the seat, a cross bar between the said members remote from the seat, an elastic member bent upon itself to form a loop surrounding the cross bar, the free extremities of the member being connected with the seat to form a yielding support therefor, said body structure also embodying folding side members for the seat, and a catch having pivotal connection with the body structure and movable therewith, said catch being adapted to engage the supporting structure to lock the parts in position, the free end of the catch being adapted to move upon and be supported by the said elastic member when the body structure is adjusted. 50 55 60

In testimony whereof I have signed my name to this specification, in the presence of two subscribing witnesses, on this 13th day of February A. D. 1908.

FRANK J. BEIER.
